UNITED STATES PATENT OFFICE

SAMUEL E. BOUCHARD, OF ROCHESTER, NEW YORK, ASSIGNOR TO BAUSCH & LOMB OPTICAL COMPANY, OF ROCHESTER, NEW YORK, A CORPORATION OF NEW YORK

DESIGN FOR A NOSE BRIDGE FOR AN OPHTHALMIC MOUNTING

Application filed October 22, 1931. Serial No. 41,487. Term of patent 7 years.

To all whom it may concern:

Be it known that I, SAMUEL E. BOUCHARD, a citizen of the United States, and a resident of Rochester, county of Monroe, and State of New York, have invented a new, original, and ornamental Design for a Nose Bridge For an Ophthalmic Mounting, of which the following is a specification, reference being had to the accompanying drawings, forming a part hereof.

Fig. 1 is a front view of a nose bridge for an

ophthalmic mounting embodying my new design.

Fig. 2 is a top plan view of same.

Fig. 3 is a sectional view taken on line 3—3 of Fig. 1.

I claim:

The ornamental design for a nose bridge for an ophthalmic mounting substantially as shown.

SAMUEL E. BOUCHARD.
